UNITED STATES PATENT OFFICE

FRED H. WHITMAN, OF MILWAUKEE, WISCONSIN, ASSIGNOR TO A. O. SMITH CORPORATION, OF MILWAUKEE, WISCONSIN, A CORPORATION OF NEW YORK

THREAD GAUGE

Application filed March 12, 1928. Serial No. 260,873.

The invention relates to a device for gauging external threads, and its purpose is to produce an external thread gauge including various novel and improved structural characteristics in combination adapted to render the device particularly efficient and accurate in the performance of its intended service.

The novel features of my invention will become apparent from the full description 10 thereof now to be made.

Figure 1 is a front elevational view, partially sectioned and broken away, of a thread gauging device made according to the invention.

Fig. 2 is a sectional view thereof, on line 15 2-2 in Fig. 1, disclosing, in dotted lines, a section of pipe the thread of which is set in the device ready to be gauged.

Fig. 3 is an enlarged detail sectional view disclosing the manner in which the metal band of the gauge is seated in the pipe thread during the gauging operation.

The present thread gauging device consists, generally, of a housing 10, preferably 20 of aluminum, for a system of manipulatable levers 11 associated with a metal band 12, a constant-friction tightener 13 for actuating said levers to tension said band, and a dial compartment 14 having a dial sector 15 and 30 a lamp 16.

The housing 10 includes a cylindrical part 17 having spaced and parallel front and rear walls, designated 18 and 19, respectively, and also includes an annular extension 20, 35 back of said rear wall and perpendicular thereto, for the reception of a threaded pipe, or similar member, the external thread 21 of which is to be gauged. The front wall 18 of the housing is an integral part thereof, while 40 the rear wall 19 consists of an integral inwardly extending annular flange 22, providing an annular seat 23 for the pipe end, and a circular plate 24 conveniently attached to said annular flange, in a manner not 45 shown.

A fitting 25 secured upon the front wall 18 of the housing, as at 26, provides a bearing 27 adjacent a central opening 28 through 50 said front wall, and said fitting is for a further purpose to be explained.

A short shaft 29, arranged centrally of the cylindrical part of the housing at right-angles to the front and rear walls thereof, has its forward end journaled in the bearing 27 and its rearward end journaled in a central bearing 30 of the plate 24. 55

The metal band 12 is preferably circular in cross-section, and is of material of high tensile strength and having a low coefficient of expansion. One end of said metal band 60 is attached to a desirably adjustable clevis 31 situated in a pocket 32 of the cylindrical part 17 of the housing, and the length of the metal band extends circumferentially within the housing adjacent a single spiral groove 65 33 cut on the inner bore of said cylindrical part 17 of the housing and adapted to accommodate expansion of the enveloping metal band in order that it can be applied to or released from an external thread. The 70 other end of the metal band 12 is pivotally attached, as at 34, to a lug 35 integral with and perpendicular to a lever 36 adjacent the front wall 18 and mounted, as at 37, upon the short shaft 29. A bevel gear 38 keyed to 75 said short shaft and located within the opening 28 of the front plate, is also keyed to the hub of the lever 36, as at 39, to lock said lever 36 upon said short shaft.

The dial sector 15 is preferably situated 80 in the dial compartment 14 to be about in alignment with the plate 24, and said dial sector is desirably of ground glass conveniently graduated, as at 40. The lamp 16 is back of the dial sector, and a sight piece 85 41 in an extension 42 of the front wall of the housing is in transverse alignment with the dial sector and lamp.

A pointer lever 43 rotatably mounted upon the short shaft 29 between the lever 36 and the bearing 30, as at 44, has a pointer 45 adapted to travel across the front of the dial sector in spaced relation thereto. A coil spring 46 having one of its ends secured to the pointer lever 43, as at 47, and its other end secured to the housing, as at 48, is adapted to urge said lever 43 in direction toward the side of the housing having the clevis 31, and a protuberance 49 upon the end of the pointer lever opposite its pointer is adapted 100

to engage an adjustable stop 50 upon said housing to limit the extent to which said coil spring can move said pointer lever.

An actuating lever 51 for the pointer lever 43 is pivotally mounted, as at 52, upon the inner face of the extension 42 of the front wall 18, and is pivotally associated, as at 53, with a part of said pointer lever situated not very far distant from its axis. A pin 54, situated in the lever 51 a short distance from its axis, protrudes outwardly into the path of travel of an upstanding hook 55 upon an integral arm 56 of the lever 36.

In Figs. 1 and 2 of the drawings, the metal band 12 and the levers 36, 43 and 51 are all disclosed in their inoperative positions. That is to say, the metal band is in its natural or expanded condition and lies within the spiral groove 33, and the lever 36 is situated to locate the hook 55 in spaced relation to the pin 54 upon the lever 51, at the left of said pin in Fig. 1. In this condition of the parts, a pipe the external thread 21 of which is to be gauged is inserted into the annular extension 20 of the housing and, as shown, against the seat 23 at the base thereof.

Mechanism for actuating the lever 36 to contract the metal band 12 to cause it to seat in the pipe thread, as disclosed in Fig. 3, is constituted by the constant-friction tightener 13, manipulation of said tightener to contract the band rotating said lever 36 in direction causing the hook 55 to move from left to right in Fig. 1, toward the pin 54.

Of said constant-friction tightener, 57 indicates driving friction discs splined to the inner bore of a handle 58 for the thread gauge, and 59 represents driven friction discs splined to an arbor 60 suitably journaled in the fitting 25 and having a keyed bevel gear 61 which meshes with the bevel gear 38. Each of the discs 57 is separated from the next adjacent disk 57 on either side by a disc 59, and vice versa. A coil spring 62 upon the arbor, between a washer 63 splined to said arbor adjacent the friction discs and a washer 64 at the outer portion of the arbor and backed by a nut threaded on the arbor, urges said discs into engagement with an inner radial wall 66 of the handle and into frictional engagement with each other. By turning the nut 65 on the arbor the pressure between the discs, and consequently, the driving effort which can be transmitted into the arbor by the handle, can be nicely adjusted.

It will be evident that rotation of the handle 58 in proper direction will cause the bevel gear 61 to turn the bevel gear 38 to rotate the lever 36 in direction from left toward right in Fig. 1, to thus contract the metal band and at the same time move the hook 55 toward the pin 54 upon the lever 51. The arrangement is such that when said hook reaches engaging position with said pin, said metal band is contracted to the gauge of a

thread of the largest dimension capable of being measured by the particular device disclosed, and the position of the pointer lever is determined by the actuating lever 51, as will be obvious, so that the pointer 45 gives a reading corresponding directly to the gauge at which said metal band is set, and should said metal band at this time be seated in an external thread, such as 21, the pointer will indicate the gauge of this thread. Provided the thread is of smaller gauge, the lever 36 is caused to move farther to the right in Fig. 1 until the metal band becomes seated upon the thread. The hook 55, naturally, causes the pin 54 to move with said lever 36, and the lever 51 transmits the motion to the pointer lever to carry the pointer across the dial sector against the action of the coil spring 46. The position of said pointer with respect to the graduations upon the dial sector when the metal band is seated against a particular thread, will indicate the actual gauge of said thread, as is evident.

As is also evident, levers such as 36, 43 and 51 can have their fulcrums and pivots so arranged and related as to magnify any preferred number of times at the pointer the variation in the pitch lines of different threads gauged, the variation being magnified in the particular device shown about twelve times.

The friction disc arrangement of the constant-friction tightener makes provision for placing the metal band 12 under exactly the same tension each time said band is seated to an external thread, and any attempt to increase this tension will but cause the driving discs 57 to rotate relatively to the driven discs 59.

Having thus described my invention, what I claim and desire to secure by Letters Patent of the United States, is:

1. A gauge for externally threaded members comprising a metal band of substantially circular cross-section having overlapping end portions and adapted to envelop an externally threaded member to be gauged, means holding one end of said band in stationary position, a lever attached to the other end of said band, means for actuating said lever to contract said band to cause the same to seat between the threads, a graduated dial sector, a pointer associated therewith, and mechanism associated with said lever and pointer for transmitting the motion of said lever to said pointer to cause it to move over said dial sector, whereby the pointer will indicate the gauge of a thread upon which said band is seated.

2. A gauge for externally threaded members comprising a metal band of substantially circular cross-section having overlapping end portions and adapted to envelop an externally threaded member, means holding one end of said band in stationary position, a

lever attached to the other end of said band, means for actuating said lever to contract said band to cause the same to seat between the threads, a graduated dial sector, a pointer associated therewith, and mechanism associated with said lever and pointer for transmitting the motion of said lever to said pointer to cause the pointer to have movement over the dial sector of greater magnitude than the movement of said lever, whereby the pointer will indicate the gauge of a thread upon which said band is seated in such manner that the variation in the pitch lines of different threads gauged will be magnified upon said dial sector.

3. A thread gauge comprising a metal band adapted to envelop an external thread, means holding one end of said band in stationary position, a lever attached to the other end of said band, an axis upon which said lever is fixed, means for rotating said lever axis to actuate said lever to contract said band to cause it to seat against said thread, a graduated dial sector, a pointer associated therewith, and mechanism associated with said lever and pointer for transmitting the motion of said lever to said pointer to cause the pointer to have movement over the dial sector of greater magnitude than the movement of said lever, said mechanism comprising a rotatable pointer lever mounted radially of said lever axis and having said pointer, resilient means normally holding said pointer lever adjacent an end of said dial sector, a rotatable actuating lever for said pointer lever mounted in spaced relation to and extending in the general direction toward said lever axis, a pivotal connection between the free end portion of said actuating lever and an intermediate part of said pointer lever, a pin upon said actuating lever adjacent its axis, and means upon the metal band contracting lever adapted to move said pin in direction away from said pointer to swing said pointer across said dial sector, whereby the pointer can indicate the gauge of a thread upon which said band is seated in such manner that the variation in the pitch lines of different threads gauged will be magnified upon said dial sector.

4. In a thread gauge, a metal band adapted to envelop an external thread, a cylindrical housing for said band and having a spiral groove in its inner bore in which said band is normally situated, means holding one end of said band in stationary position in the housing, a lever attached to the other end of said band, and mechanism for actuating said lever to contract said band to cause it to be removed from said spiral groove and to seat against said thread.

5. In a thread gauge, a metal band adapted to envelop an external thread, means holding one end of said band in stationary position, a lever attached to the other end of

said band, and a constant-friction tightener for actuating said lever to contract said band to cause it to seat against said thread and for preventing tensioning of said band beyond a predetermined degree.

6. In a thread gauge, a metal band adapted to envelop an external thread, means holding one end of said band in stationary position, a lever attached to the other end of said band, an axis upon which said lever is fixed, and mechanism for rotating said lever axis to actuate said lever to contract said band to cause it to seat against said thread, said mechanism comprising an arbor, a gear connection between said arbor and lever axis, driven friction discs upon said arbor, an operating handle about said arbor, and driving friction discs upon said handle and interposed between said driven friction discs.

7. In a thread gauge, a housing, a metal band therein adapted to envelop an external thread, means holding one end of said band in stationary position in said housing, a lever attached to the other end of said band, an axis upon which said lever is fixed, and a constant-friction tightener for rotating said lever axis to actuate said lever to contract said band to cause it to seat against said thread, said tightener comprising an arbor, a gear connection between said arbor and lever axis, driven friction discs upon said arbor, a handle for said housing and about said arbor, driving friction discs upon said handle and interposed between said driven friction discs, and means for yieldingly pressing said driving and driven friction discs against each other.

8. A gauge for an externally threaded member comprising a flexible metal band adapted to envelop the external threads of a member, actuating means to cause said band to engage said threads including means to prevent the tensioning of said metal band beyond a predetermined degree, and means associated with said actuating means for indicating the gauge of said threaded member.

9. A gauge for an externally threaded member comprising a flexible metal band adapted to envelop the external threads of a member, means holding one end of said band in stationary position, a lever attached to the other end of said band, means for actuating said lever to contract said band to cause the same to be seated between said threads including means to prevent actuation of said lever to contract said band beyond a predetermined degree relative to said threads and indicating means associated with said lever for determining the gauge of said threaded member upon which said band is seated.

10. A method for determining the gauge of a tapered threaded member which comprises passing a metallic band around the circumference thereof at a predetermined distance from the end of the threaded member, ex-

erting a predetermined limited tension on said metal band to cause the same to seat between the threads of said member, and registering the measurement of the circumference thereof.

5 11. A gauge for threaded members comprising a housing adapted to envelop a portion of a threaded member to be gauged, a shoulder in said housing adapted to abut the end of the member, a flexible metal band spaced from said shoulder and adapted to envelop said member and to be seated between the threads thereof, means for causing said metal band to be thus seated, and indicating means controlled by said band-seating means for indicating the gauge of the member.

10 12. A gauge for externally threaded members comprising a metal band having overlapping end portions and curved side faces adapted to engage opposing faces of adjacent threads of a threaded member to be gauged with the opposing faces of the threads tangent to the curved faces of the metal band, means holding one end of said band in stationary position, a lever attached to the other end of said band, means for actuating said lever to contract said band to cause the same to seat between the threads, a graduated dial sector, a pointer associated therewith, and 15 mechanism associated with said lever and pointer for transmitting the motion of said lever to said pointer to cause it to move over said dial sector, whereby the pointer will indicate the gauge of a thread upon which said band is seated.

20 35 In testimony whereof I have signed my name at Milwaukee, Wisconsin, this 28th day of February, 1928.
